UNITED STATES PATENT OFFICE.

JOHN D. ROGERS, OF PRINCETON, WEST VIRGINIA, ASSIGNOR OF ONE-HALF TO H. C. ELLETT, OF PRINCETON, WEST VIRGINIA.

COMBUSTION-CHAMBER FOR LOCOMOTIVES.

1,175,299.

Specification of Letters Patent. Patented Mar. 14, 1916.

Application filed January 7, 1915. Serial No. 998.

To all whom it may concern:

Be it known that I, JOHN D. ROGERS, citizen of the United States, residing at Princeton, in the county of Mercer and State of 5 West Virginia, have invented certain new and useful Improvements in Combustion-Chambers for Locomotives, of which the following is a specification.

My invention relates broadly to new and 10 useful improvements in the construction of locomotive fire boxes and boilers.

The present state of the art recognizes the desirability of placing in the fire box a bridge wall which is of fire brick and serves 15 to provide between the forward ends of the grate and the flue sheet a combustion chamber into which an additional supply of air is admitted for the purpose of producing a complete combustion of the gases before the 20 gases enter the fire tubes. In the majority of cases, the bottom of such a combustion chamber is formed by a removable plate or false bottom, the inner face of which is lined with fire brick or some similar material. It has 25 often been found that such fire clay or brick lining disintegrates after being in use but a short time. This is, of course, an undesirable feature, and one causing a great deal of expense in repair work.

30 The primary object of my invention is, therefore, to provide for the fire box of a locomotive, a combustion chamber, the bottom of which is constituted by concentrically arranged, spaced metal shells or plates 35 which define a water wall communicating with the crown of the boiler.

A further object of the invention is to eliminate the bearer members, the false bottom plates, and the fire brick lining customarily employed in constructing the combustion chamber in a locomotive fire box, thereby reducing the cost of manufacture and up-keep.

Another object is to construct the combustion chamber in such manner that the weight imposed upon the forward transverse member of the mud ring is materially less than heretofore, so that the mud ring may be of smaller size and resultantly cheap as regards first cost.

A still further object is the provision of a combustion chamber, the bottom of which is defined by a smooth curved metallic plate, adapting the combustion chamber to be 55 easily and quickly cleaned.

An additional object is to reduce to a minimum the tendency of choking in the bottom flues by locating the cleaning hole or hopper in juxtaposition to the flue sheet.

An object of equal importance with the foregoing is to so design and construct the combustion chamber that the throat sheet of the boiler may be made as shallow as is desired without any attending disadvantages.

A still further object of this invention is to so construct the combustion chamber that the actual heating surface in the boiler will be increased.

The above recited and other incidental objects of a similar nature, which will be hereinafter more specifically treated, are accomplished by such means as are illustrated in the accompanying drawings, described in the following specification, and then more particularly pointed out in the claim, which is appended hereto and forms a part of this application.

With reference to the drawings, wherein there has been illustrated the preferred embodiment of this invention as it is reduced to practice, and throughout the several views of which similar reference characters designate corresponding parts, Figure 1 is a vertical longitudinal section taken medially through the fire box of a standard locomotive; and Fig. 2 is a compound sectional view, the left hand side of which is taken on the line 2-2 of Fig. 1, and the right hand side of which is taken on the line 2^a-2^a of Fig. 1.

In the accompanying drawings, the locomotive fire box illustrated is of the well-known type, including as it does a grate chamber A and a combustion chamber B 95 which is located between the forward end of a grate C and a flue sheet D, and is defined by a bridge wall E.

The bridge wall E is formed from a plurality of fire bricks 10, which are superposed and are provided with vertically extending air passages, indicated by dotted lines at 11. Through these air passages 11 extend pipes 12, the upper terminals of which lead into the flared openings 13 of the uppermost bricks, and the lower terminals of which extend below the forward transverse member 14 of the fire box mud ring and carry air inlet funnels 15.

In the present construction, the transverse

bearer plate, such as has been heretofore employed in supporting the bridge wall, has been eliminated, and the bearer bracket 16 is has been substituted. This bracket 16 is 5 formed from plate metal and is substantially L-shaped in cross section. One portion of this bracket 16 is secured by rivets 17 to the rear face of the mud ring 14. The horizontally arranged portion of the bracket receives, as shown in Fig. 1, the case bricks 10 of the bridge wall E.

Air may enter through the funnels 15 and escape into the fire box through the flared 15 openings 13, so that the gases liberated from the burning coal in the grate chamber A will be sufficiently thinned to produce complete combustion of all gases as they pass through the combustion chamber B.

The bottom of the combustion chamber 20 consists in a water wall 18. This water wall 18 is defined by inner and outer metal plates 19 and 20 which are maintained in the desired spaced relation by stay bolts 21. The central portion of these plates 19 and 20 25 are curved downwardly and are provided with centrally located openings which define the cleaning hole 22. Any suitable door of air tight construction may be studded over the opening 22. Rivets, indicated at 23, 30 are, of course, employed in connecting the edge portions of the plates 19 and 20 at the opening 22. The space between the edges of the plates is, of course, calked at 24 to prevent the leakage of water from the water 35 wall 18. The rear transverse edges of the shell or plate members 19 and 20 are engaged about the mud ring member 14, as shown particularly in Fig. 1.

It will be seen, upon reference to the drawings, that the wall 19 slopes in all directions 40 toward the opening 22 so that the cleaning of the combustion chamber may be easily and readily accomplished. It will also be seen that, since the cleaning hole is located 45 relatively close to the lower flues or fire tubes, it will be an easy matter to frequently clean these flues and thus prevent their clogging.

The forward edge of the plate member 19 50 is connected by rivets 25 to the lower edge of the flue sheet D in the manner best shown in Fig. 1. The member 20 in reality consists in a continuation of the bottom portion of the boiler member 26, as will be noted 55 upon reference to Fig. 1. In the same manner, the member 19 really consists in a continuation of the inner shell 27 of the fire box side wall.

The heating surface is obviously increased 60 in the present construction by the elimination of the fire brick lining in the combustion

tion chamber, and substituting therefor a water wall through which water from the boiler may circulate.

It has been found in practice that a combustion chamber having the construction above described is less expensive both as regards cost of installation and up-keep than combustion chambers in which a false bottom and a fire brick lining are employed. 65 It has also been found that one of the material factors making for the cheapness of manufacture and installation of the combustion chamber is the material reduction in the weight which must be carried by the 70 mud ring. The weight imposed upon the mud ring being lessened, it is obviously possible to materially reduce the size and hence the cost of the mud ring.

In reduction to practice, it has been found 75 that the form of this invention illustrated in the drawings, and referred to in the above description, as the preferred embodiment, is the most efficient and practical; yet realizing that the conditions concurrent with the 80 adoption of this device will necessarily vary, it is desirable to emphasize the fact that various minor changes in details of construction, proportion and arrangement of parts may be resorted to, when required, without 85 sacrificing any of the advantages of this invention, as defined in the appended claim.

Having thus described the invention, what is claimed as new is:—

In a locomotive fire box, a bridge wall defining a combustion chamber which is located between the forward end of the grate and the rear flue sheet, a transverse metal bracket secured to the mud ring of the fire box, said bracket constituting a support for 100 the bridge wall, and a pair of spaced metal plates forming the bottom of the combustion chamber and defining a water wall which is in communication with the boiler, the central portions of the plates being provided 105 with registering openings and being curved downwardly providing a discharge opening whereby material may be removed from the combustion chamber from beneath the locomotive, the edge portions of the plates at the 110 openings thereof being connected and calked to form a water tight wall, the rear transverse edges of the plates being secured against the opposite faces of the forward transverse member of the fire box mud ring. 115

In testimony whereof I affix my signature in presence of two witnesses.

JOHN D. ROGERS. [L.S.]
